UNITED STATES PATENT OFFICE.

THOMAS E. MURRAY, JR., OF NEW YORK, N. Y.

PROCESS OF AND APPARATUS FOR ELECTRICALLY DIVIDING METAL PLATES OR BLOCKS.

1,233,691.

Specification of Letters Patent.

Patented July 17, 1917.

Application filed May 5, 1917. Serial No. 166,563.

To all whom it may concern:

Be it known that I, THOMAS E. MURRAY, Jr., a citizen of the United States, residing at New York, in the county of New York and State of New York, have invented a certain new and useful Improvement in Processes of and Apparatus for Electrically Dividing Metal Plates or Blocks, of which the following is a specification.

10 The invention is a process of and apparatus for electrically dividing metal plates or blocks.

15 The plate or block to be divided is placed in contact with two electrodes of a width substantially corresponding to the width of said plate and separated by an interval corresponding to a kerf of predetermined dimensions so as to bridge said interval. There is then established through said electrodes and plate a current of sufficient strength to melt the metal of the portion of the plate which bridges said interval, which melted metal then escapes through said interval, leaving the plate divided into two 25 parts.

In the accompanying drawings—

Figure 1 is a vertical section of the electrodes and plate to be divided. Fig. 2 is a perspective view of the divided plate. 30 Similar letters of reference indicate like parts.

A, A' is a bed or support of refractory insulating material, such as porcelain or cement, formed in two separated parts. B and C are electrodes thereon. Each electrode is formed in two parts a, b and each electrode is of a width substantially corresponding to the width of the divided sections of said plate. The plate D to be divided rests upon the lower parts a of the electrodes so as to bridge the gap or interval b between the opposing faces or edges of said parts which interval is to correspond in dimensions to the predetermined kerf to be made between the divided sections of said plate. The upper parts c of the electrodes are placed above the plate D, with a gap d between them, preferably of the same width as gap b. The parts of electrode B are clamped together by a headed bolt E, the head of which is received in a countersink in bed A. The parts of electrode C are clamped together by a headed bolt F, the head of which is also received in a counter-

sink in bed A. The outer edges of the parts 55 of electrode C are slotted, as shown at G, to receive bolt F, so that when said bolt is loosened, electrode C may be moved nearer to or farther from electrode B, so as to vary the width of gaps b, d. One terminal leading from any source of electrical current is connected to electrode B, and the other terminal to electrode C.

The operation is as follows: The gaps b, d are first adjusted so as to determine the 65 width of the kerf H, Fig. 2 to be made. The current is then established, with the result that the metal of the portion of plate D which bridges gap b will be melted, and will flow downwardly and through the gap 70 b, and so out of the opening between the parts A, A' of the bed. As this melting occurs along the whole width of the plate, as shown in Fig. 2, said plate becomes divided into two parts by the kerf H, as 75 shown. This operation is practically instantaneous. The gaps b, d and hence the kerf may be made as narrow as desired.

The term "substantially corresponding to the width of said plate" herein used, means 80 that the width of the electrodes and the width of the plate to be divided are to correspond, so that when the current passes, the kerf electrically formed will completely separate the two sections of the plate. This 85 result will obviously follow when the width of the electrodes is precisely equal to or greater than the plate. What I desire to point out is that it will also follow even when the electrodes are slightly less in 90 width than the plate because of the spreading of the heating effect upon the metal, and the consequent softening thereof from the outer edges of the electrodes to the outer edges of the plate; and my object in making 95 this statement is to guard against any minute interpretation of the claims designed to exclude such slight variation in correspondence of the outer edges of the plate and the outer edges of the electrodes.

While I have here shown the kerf H as straight, it will be obvious that it may also be curved, or otherwise depart from a straight line joining the opposite edges of the plate to be divided.

I claim:

1. The process of dividing a metal block or plate, which consists in electrically melt-

ing a portion of said plate to form a kerf of predetermined dimensions, whereby said plate is separated into two sections.

2. The process of dividing a metal block or plate, which consists in first placing said plate in contact with electrodes of a width substantially corresponding to the width of said plate and separated by an interval corresponding to a kerf of predetermined dimensions to be made between the divided sections of said plate, and second, establishing an electrical current between said electrodes, whereby the entire portion of said plate between and bridging said electrodes is melted and caused to flow from between said sections.

3. An apparatus for dividing a metal block or plate, comprising electrodes of a width substantially corresponding to the width of said plate and separated by an in-

terval corresponding to a kerf of predetermined dimensions to be made between the divided sections of said plate, and means for clamping said plate in contact with said electrodes to bridge said interval.

4. An apparatus for electrically dividing a metal plate, as in claim 3, one of said electrodes being adjustable to vary the width of said gap.

5. An apparatus for electrically dividing a metal plate, as in claim 3, each of said electrodes being formed in two parts, and means for clamping said plate between said parts.

In testimony whereof I have affixed my signature in presence of two witnesses.

THOMAS E. MURRAY, JR.
